UNITED STATES PATENT OFFICE

JOAH LODGE, OF HUDDERSFIELD, AND MARK OLDROYD, OF DEWSBURY,
COUNTY OF YORK, ENGLAND.

MACHINE FOR STRETCHING AND WINDING-ON WOVEN FABRICS, &c.

SPECIFICATION forming part of Letters Patent No. 308,081, dated November 18, 1884.

Application filed February 23, 1884. (No model.) Patented in England October 13, 1881, No. 4,465.

To all whom it may concern:

Be it known that we, JOAH LODGE, of Huddersfield, and MARK OLDROYD, of Dewsbury, both in the county of York, England, and citizens of the Kingdom of Great Britain, have 5 jointly invented certain Improvements in Machines for Stretching and Winding-On Woven Fabrics &c., of which the following is a specification.

10 This invention has special reference to the finishing of woven fabrics, the principal object of the invention being to stretch the fabric, both in length and width, while it is passing through the machine.

15 With respect to woolen fabrics, the several processes of blowing, boiling, or steaming have hitherto been done by winding the said fabric upon a roller or cylinder, and in order that the cloth might be wound upon the said 20 roller or cylinder evenly one or more attendants have been employed to open and stretch the twisted cloth to its proper width during the process of winding-on, and as the cloth was frequently saturated with boiling water 25 there was some difficulty in handling it.

Our invention seeks to obviate these difficulties; and it consists, partly, in a combination of the endless carrying-chains provided with pins and their bearing-pulleys with the 30 take-up cylinder, the cylinder or beam which receives the fabric, and their operative or driving mechanism, whereby the take-up cylinder, which is arranged close to the pins, takes the fabric the moment it leaves the pins, 35 and the fabric has no opportunity to shrink back.

It also consists, partly, in the mechanism, which will be hereinafter described, for maintaining a uniform peripheral speed of the cylinder or beam upon which the fabric is wound; partly in the combination of parts or elements of mechanism whereby the endless chains are spread apart, and partly in the construction of the steaming apparatus arranged under the 40 passing fabric, all as will be fully hereinafter described, and defined in the claims.

The machine may also be used for distending the cloth and removing the washing and milling creases therefrom, the cloth being fed 45 to the chains and beaten with sticks by the

attendants, after which it is cutted by the ordinary cutting apparatus.

In order that our invention may be fully understood, we herein give reference to the accompanying sheets of drawings illustrative 55 thereof.

Figure 1 is a side elevation of the machine, and Fig. 2 is a plan view thereof. Fig. 3 shows the opposite side to Fig. 1. Fig. 4 is a view of the driving end of the machine, and Fig. 5 is a cross-section.

A is the frame-work of the machine, and B are two endless chains, which pass over the pulleys C C' C² C³, which are carried by the shafts D and E, on which they are splined. 65 These chains rest and slide in grooved strips B' B', which have pendent nuts a' a' and a'', through which pass screw-threaded shafts F, F', and F'', which are journaled in the main frame and bear worm-wheels G, which mesh 70 with worms H on a shaft, J. The shafts F F' F'' have right and left screws on their opposite ends, and rotation of shaft J in one direction sets the strips B' and the chains B in or closer together, while its rotation in the opposite direction sets them out, or farther apart. 75

In order that the pulleys C² C³ may move in and out with the chains, we provide the nuts a'' with forked branches b'' to engage circumferential grooves in the bosses of the pulleys. 80 At the other end of the machine we provide a means whereby the pulleys C C' and chains may be moved in a little independently of the strips B'. This comprises clutch-levers K, (see at right of Fig. 5,) the inner ends of 85 which are hinged to nuts a', engaged by screw-shaft F as fulcrums, while the levers engage circumferential grooves in the bosses of the pulleys.

The object of shifting the chains and pulleys 90 in and out is to suit them to fabrics of different widths, and by means of the independent movement of pulleys C C', effected by levers K, the chains may be brought a little closer together at the receiving end of the machine, so as to stretch the fabric laterally as the chains spread in moving forward. The chains are provided with pins, and the cloth, being fed thereto and properly stretched, is taken up by the roller L, from which it passes 95 100.

to the plain or perforated cylinder M and wound thereon, this cylinder being turned by means of the friction-disk N, working in contact with the plate N', mounted on the end of the shaft of the cylinder. The cylinder is mounted in the vertical bearings O, which are capable of sliding up and down the framework, and are counterbalanced by weights P acting through the segment and rack S. As the roll of cloth upon the cylinder M increases in diameter, the cylinder rises and the plate N' rises along with it, and the friction-disk N operates at a greater distance from the center of the said plate, which consequently revolves slowly, and so compensates for the increased length of cloth taken up at each revolution. The cloth is thus constantly traveling on the chains at a uniform speed. When desirable, the taking-up roller may be caused to travel faster than the chain-pulleys, and so stretch the cloth in length as well as in width. This may be effected by increasing the diameter of the disk N slightly. As this engages only by friction, it will slip if the strain becomes too great.

It will be observed that the delivery end of the chain is very close to the taking-up roller L, by which means the fabric has no sooner left the pins of the endless chain than it is seized hold of by the said roller L. Consequently the fabric which has just been stretched cannot shrink back, but will be wound upon the roller in its distended state. If required, a trough, V, containing a perforated steam-pipe, W, may be employed so as to steam the fabric. The trough V has sliding covers V', which may be moved (see Fig. 2) so as to expose more or less of the perforated steam-pipe under the moving fabric. The pipe W connects with a steam-generator or other source of supply.

This construction of machine may be used with great advantage for removing the washing and milling creases from the cloth, and this is done by means of sticks or beaters used by the workmen, who beat the cloth while in its distended state, after which it is cutted by ordinary cuttling apparatus.

The machine is driven as follows: 1 and 2 are fast and loose pulleys, on the shaft of which is a toothed pinion, 3, gearing with a wheel, 4, on a shaft, 5. On the same end of the shaft 5 is a pinion, 6, which gears with a toothed wheel, 7, mounted on the shaft D, which carries the principal chain-pulleys. The wheel 7 gears with a wheel, 8, on the shaft of the taking-up roller. The shaft 5 also carries a bevel-wheel, 9, which gears with another bevel-wheel, 10, and drives the vertical shaft 11 and friction-disk N. A hand-wheel and screw, T, are provided to regulate the pressure exerted by the disk N upon the plate

N', and the plate is supported at the back by the pulleys a, which keep it perfectly true and prevent the shaft from being strained. The cylinder M is mounted in bearings or centers at its ends, similar to lathe-centers, and it may be removed by running back one center (at the right in Fig. 4) through the medium of a rack and pinion, b. Over the chains B at the feeding end of the machine are arranged brush-wheels c. (Best shown in Figs. 1 and 2.) The fabric passes in under these brush-wheels, and they serve to press the former down upon the pins on the chains. They are not driven by gears, but are revolved by the moving fabric.

Having thus described our invention, we claim—

1. The combination of the endless chains B, provided with pins, and their bearing-pulleys, 80 with the take-up cylinder L, arranged close to the pins on the endless chains, the cylinder M, and mechanism, substantially as described, for driving the said chains and cylinders, all arranged to operate substantially as 85 set forth.

2. The combination of the cylinder M, mounted in bearings capable of playing vertically, with the disk or plate N', mounted on the axis of said cylinder M, the driving friction-wheel N, and mechanism, substantially as described, for driving said friction-wheel N, whereby the peripheral speed of the cylinder M is maintained uniform, for the purposes set forth.

3. The combination of the endless chains, the chain-pulleys C and C' and their shaft, and the grooved strips B', provided with nuts a' a'', with the screw-shafts F F' F'', means, substantially as described, for operating said 100 screw-shafts, and the clutch-levers K, pivoted to the nuts a', engaged by shaft F, and constructed to engage circumferential grooves in the pulleys C C', substantially as and for the purposes set forth.

4. The combination, with the endless chains and mechanism for carrying them, substantially as described, of the trough V, provided with sliding covers V', as shown, said troughs arranged below said chains, and the perforated 110 steam-pipe W, arranged in said trough, substantially as and for the purposes set forth.

In witness whereof we have hereunto signed our names in the presence of two subscribing witnesses.

JOAH LODGE.
MARK OL德ROYD.
